Primary Examiner—Gary D. Watson*Attorney, Agent, or Firm*—Price, Heneveld, Cooper, DeWitt & Litton[57] **CLAIM**

The ornamental design for a chair, as shown and described.

DESCRIPTION

FIG. 1 is a front perspective view of a chair, showing our new design;

FIG. 2 is a left side elevational view thereof, the right side elevational view being a mirror image thereof;

FIG. 3 is a front elevational view thereof;

FIG. 4 is a top view thereof; and,

FIG. 5 is a rear elevational view thereof.

The broken lines shown in all views represent stitching.
